UNITED STATES PATENT OFFICE

EDWARD ROSS, OF SCRANTON, PENNSYLVANIA

STENCIL DEVICE

Application filed March 1, 1929. Serial No. 343,589.

This invention relates to stencil devices, and more particularly to devices of this kind which are designed for stencilling records on the backs of binders or record books.

5 In books of this kind which are used for containing abstracts, waybills and various other records, kept, for example, by railroad and other large companies, and where a large number of such books or binders is used, it is desirable to make on the backs of these books, indications which can be readily recognized as signifying dates, departments, or the like. For example, in books of this kind, a certain colored mark on a certain portion of 10 the back may be used to indicate the year, while other stencil marks in different relative parts of the back of the book may be used to indicate different months of the year during which the records enclosed in the book were 15 filed therein.

The objects of this invention are to provide a stencilling device of this kind which is so formed as to adapt itself for use in connection with books or binders of this kind; also to provide a device of this kind in which the stencilling members are readily adjustable for positioning the same on different parts of the frame; also to improve the construction of stencilling devices of this kind in other respects hereinafter specified.

20 In the accompanying drawings:

Fig. 1 is a front face view of a stencil device embodying this invention;

Fig. 2 is a central sectional elevation there- 25 on line 2—2, Fig. 1;

Fig. 3 is a transverse section thereof on line 3—3, Fig. 1.

The stencilling device includes a frame member which is preferably made of sheet metal, but which may be made of other thin material.

This frame member in the particular construction shown is made of a single sheet of metal having the intermediate portion there- 35 of cut out or removed to form sides 5 and 6, a bottom cross member 7 and a top cross member 8, the cut out portion forming an opening 9 through which the stencilling may be done. In order to enable the frame to be 45 correctly positioned with reference to the

article which is to be stencilled, for example, with reference to the back of a book or binder, the frame is provided with a part which may engage an edge of the back of the binder or book, for example, the top edge of the binder. 55 In the particular construction shown for this purpose the upper part of the stencil frame is provided with a rearwardly extending flange 10 which may be formed by bending the part of the metal of the stencil frame rearwardly. 60 Any other means for correctly positioning the stencil frame with reference to the article to be stencilled may be provided, if desired.

The sides 5 and 6 of the frame are provided with means for definitely locating a stencil 65 in different positions with reference to the opening 9 of the stencil frame. In the particular construction shown for this purpose the side frame members 5 and 6 are provided with apertures 12 arranged so that for each 70 aperture on one of the side members 5 and 6 a corresponding aperture is positioned in the same relation to the other side member of the frame. The frame member is preferably also provided at its lower end with a slot or open- 75 ing 14, the purpose of which will be herein- after described.

The stencilling device also includes an adjustable stencilling member 15 which in the form shown is made of a strip of relatively 80 thin metal or other material having an aperture 16 of any suitable kind through which the stencilling is to be done.

This stencilling member 15 in the form shown extends cross-wise of the stencil frame 85 and is provided adjacent to its end with means for securing the stencil member into any pair of apertures 12. In the particular construction shown for this purpose, the stencil member 15 has screw threaded studs 18 secured 90 thereto and spaced apart so that the studs may enter through any pair of apertures 12. The stencil member 15 may then be secured in such position by means of clamping nuts 19.

In the use of the device described, the stencil frame may readily be positioned on the back of a book or binder by placing the rearwardly projecting positioning edge 10 on the upper edge of the back so that the opening 9 in the frame will coincide with a portion of 100

the back of a book or binder. The apertures 12 are preferably arranged in 12 pairs accurately spaced to represent the twelve months of the year. When a book or binder is to be 5 stencilled, a certain color is used through the stencil opening 14 corresponding to the year to be indicated on the book, and the movable stencil member 15 is then placed into engagement with a pair of apertures 12 corresponding 10 to the month to be indicated on the back of the book or binder. The color used through the opening 14 indicates at a glance the year to which the book belongs and the location of the other stencilled marks made through the member 15 indicates by its relative location 15 between the top edge of the book or binder back and the stencil made through the aperture 14, the month of the year to which the book belongs.

20 The device, of course, may be used in different ways. For example, the openings 14 and 16 may be employed not only for stencilling but for making certain notations, lettering or the like through these openings in 25 which case the openings serve as guides for directly locating the identification characters so made.

20 The device may also be used by first stencilling through the openings 14 or 16 or both, to form a colored background, and suitable identification characters may then be marked on this background through the openings 14 and 16. It will be understood that the openings 14 and 16 may be of different shapes than 35 those shown and may be shaped to form identification characters of other than rectangular shapes shown. It will be understood, however, that the term "stencil" as used in the description and claims applies to a device having openings therein regardless of 40 whether the openings 14 and 16 are used as stencilling or as guides for making identification characters therethrough.

45 It will also be understood that a number of different stencil members 15 may be used in connection with the frame, which stencil members may have different stencil openings or apertures therein.

Claims:—

50 1. An adjustable stencil device comprising a frame having an opening in the intermediate portion through which identification characters may be made, a stencil member adapted to be removably secured on different portions of the sides of said frame to position the same across different portions of said opening, and a positioning part extending rearwardly from said frame to hold said frame in definite relation to the article to be 55 stencilled.

60 2. An adjustable stencil device comprising a frame having an opening in the intermediate portion thereof through which identification characters may be made, a stencil member adapted to be removably se-

cured on different portions of the sides of said frame to position the same across different portions of said opening, and means for securing said member on said frame in different positions.

65 3. An adjustable stencil device comprising a frame having an opening in the intermediate portion through which identification characters may be made, a stencil member adapted to be removably secured on different portions of the sides of said frame to position the same across different portions of said opening, means for securing said member on said frame in different positions, said means including studs on said stencil member adapted 70 to extend through apertures in said frame, and means engaging said studs to clamp said member on said frame.

75 4. A stencil device including a frame part having a single large opening in the middle portion thereof, a stencil member extending across said opening, and cooperating parts on said frame part and said stencil member for securing said stencil member in a plurality of predetermined positions relatively to 80 said opening in the frame part.

85 5. A stencil device including a frame part having a large opening and a small opening through which identification characters can be made, a stencil member extending across 90 said large opening, means on said frame part and said stencil member for securing said stencil member to said frame part in different positions relatively to said opening, said stencil member having apertures through 95 which identification characters can be made through said large opening.

100 6. An adjustable stencil device for indicating dates on articles including a frame part having an enlarged opening in the middle portion thereof, a stencil member formed to extend across said opening and having an aperture through which identification characters can be made on an article through said 105 large opening of said frame to indicate lesser periods of time, means on said frame and said stencil member for securing said stencil member in different positions relatively to said frame for indicating said lesser periods by the location of said indications relatively 110 to said large opening, a small opening in said frame part through which an identification character corresponding to a longer period of time may be made, and means extending rearwardly from said frame part to engage an article to be stencilled for locating said frame part in definite relation to an article.

115 7. An adjustable stencil device including a frame part having the middle portion thereof forming an opening through which identification characters may be made, a small opening below said first mentioned opening, a stencil member adapted to extend crosswise of said frame part across said first men-

tioned opening, parts on said stencil member adapted to engage in apertures in said frame to position said stencil in different locations from the ends of said frame, means for securing said stencil member in several positions on said frame, and a rearwardly bent integral portion of said stencil frame which is adapted to engage with an edge of the part to be stencilled for positioning said frame in
5 definite relation to the part to be stencilled.
